UNITED STATES PATENT OFFICE.

RICHARD MAX EATON, OF NIAGARA FALLS, NEW YORK, ASSIGNOR, BY MESNE ASSIGNMENTS, TO A. L. SCHELLHAMMER.

ELECTRIC LAMP.

Application filed January 26, 1922. Serial No. 531,920.

To all whom it may concern:

Be it known that I, RICHARD MAX EATON, a citizen of the United States, residing at Niagara Falls, in the county of Niagara and State of New York, have invented certain new and useful Improvements in Electric Lamps, of which the following is a specification.

My invention relates to improvements in electric lamps, and has particular reference to such a device which is portable, and is adapted to be used as a flash light.

An important object of the invention is to provide means whereby the electric lamp may be detachably mounted upon the barrel of a firearm, in a secure and convenient manner, and may be thus employed in providing light when shooting the firearm in the dark.

A further object of the invention is to provide a clip for detachable connection with the barrel of the firearm, and also having detachable connection with the body portion of the lamp, such clip affording proper vision of the sight of the firearm, when in use.

A further object of the invention is to provide means whereby the lamp may be carried within the sleeve of the user, and connected with the garment of the user, in a manner to prevent the device from being lost, and to permit of its convenient withdrawal when desired.

A further object of the invention is to provide means for adjusting the focus of the light by shifting the bulb with respect to the lens, whereby the device may be employed to produce a spot light or flood light, as desired.

A further object of the invention is to improve the construction of the lamp in general, providing an organization which is compact, strong and durable.

Other objects and advantages of the invention will be apparent during the course of the following description.

In the accompanying drawings, forming a part of this specification, and in which like numerals are employed to designate like parts throughout the same.

Fig. 1 is a side elevation of an electric lamp embodying my invention, showing the same mounted upon a pistol,

Fig. 2 is a central vertical longitudinal section taken through the lamp, the clip being omitted,

Fig. 3 is a horizontal section at right angles to Fig. 2, taken on line 3-3 of Fig. 1,

Fig. 4 is a front end elevation of the device,

Fig. 5 is a rear end elevation.

Fig. 6 is a perspective view of the elements embodied in the circuit of the lamp, the same being separated,

Fig. 7 is a perspective view of the attaching clip,

Fig. 8 is a diagrammatic view of the circuit of the lamp,

Fig. 9 is a perspective view of the lamp arranged within the sleeve of a garment and showing its manner of attachment, and,

Fig. 10 is a perspective view of the attaching element.

In the drawings, wherein for the purpose of illustration is shown a preferred embodiment of my invention, the numeral 15 designates a preferably cylindrical casing, constituting the body portion of the device. This casing is preferably provided with inwardly spun annular flanges 16 and 17, spaced, as shown.

An outwardly bulging flange 18, in the forward end of the casing, receives and holds a lens 19.

The numeral 20 designates a spherically curved reflector, provided at its forward end with an outwardly extending annular flange 21, engaging behind the flange 16. This flange 21 is held against the flange 16 by an electrical insulating sleeve 22, as shown.

The numeral 23 designates a cylindrical cap, which is adapted to be detachably mounted upon the casing 15, the cap and casing being preferably formed of sheet metal. The cap 23 is provided with one or more inwardly projecting portions 24, adapted to pass into L-shaped slot or slots 25, cut in the rear end of the casing 15. By this means the cap is held upon the casing against accidental displacement. This cap carries the various elements of the circuit.

The numeral 26 designates a metallic sleeve, having its rear end open and provided with a flange 27. At its forward end the sleeve is provided with an inwardly ex-

tending flange 28. The sleeve 26 passes through the central opening of an insulating element or ring 29 and the flange 27 is held between this insulating ring and the end of 5 the cap 23, and is in electrical contact therewith. An insulating disk or plate 30 is arranged upon the rear face of the cap 23, and a metallic plate 31 is disposed upon the rear face of the insulating plate 30. A metallic 10 screw 32 passes through the plate 31, plate 30, cap 23, and engages within an opening 33 in the insulating element 29, and serves to bind these parts together. Particular attention is called to the fact, at this point, 15 that the screw 32 has electrical contact with the metallic plate 31, but is insulated from the cap 23, such screw passing through an opening 34, which is larger in diameter than the screw. The numeral 35 designates a 20 metallic screw passing through the insulating plate 30 the cap 23 and the insulating element 29, and serves to clamp these parts together. The screw 35 is insulated from the rear plate 31, as its head is arranged 25 within a recess 36, formed in this plate, and out of electrical contact with the plate. The screw 35 also passes through an opening 37, in the cap 23, which opening is much larger in diameter than the screw, and 30 hence the screw has no electrical contact with the cap. The screw 35 is of course metallic.

The numeral 38 designates a sliding contact element, forming one part of a switch, 35 the other part of which is formed by the forward end of the screw 35, these parts being in alignment when the cap 23 is placed upon the rear end of the casing 15 and turned slightly so that the extension 24 enters the transverse end of the L-shaped slot 25. The contact element 38 is shifted longitudinally by means of a stud 39, operating in a slot 40, and this stud is connected with a push button 41. The forward end 40 of the contact element 38 is slightly curved, as shown at 42, to engage upon opposite sides of a depression 43, in the casing 15, thereby serving to hold the contact element 38 in the forward or rear shifted position. 45 It is obvious that when the contact 38 is shifted rearwardly so that it engages the screw 35, such screw will then have electrical connection with the casing 15.

The numeral 42' designates a metallic 50 socket, having a flange 43' at its rear end, extending outwardly, as shown. A compressible coil spring 44 is arranged within the sleeve 26, between the flange 28 and the flange 43'. This spring tends to move 55 the socket 42' rearwardly within the sleeve 26. The numeral 45 designates an electric bulb, having an exterior terminal 46, screw threaded within the slidible socket 42', and an interior terminal 47, which is in contact 60 with an adjusting element or screw 48, hav-

ing a milled head 49. The screw 48 has no electrical contact with the cap 23, as it passes through an enlarged opening 50, but this screw has electrical contact with the outer plate 31 as it has screw threaded engagement with this outer plate, at 51. By turning the screw 48, it will of course be moved longitudinally, and this will shift the socket 42' and the bulb longitudinally, thereby varying the focal distance of the bulb with respect to the lens. By this means, the device may be employed to produce a spot light or a flood light.

Detachably connected with the screws 32 and 35 are plugs 52 and 53, having connection with wires 54 and 55, which are connected with the opposite pole of a source of current 56, which may be a dry cell.

As more clearly shown in Figs. 1 and 7, the numeral 57 designates a clip, adapted to 85 be mounted upon the barrel of a pistol. This clip is preferably formed of sheet metal and embodies an upper hollow portion 58, V-shaped in cross section, the sides of which are connected by means of rivets 59 or the like. Extending downwardly and outwardly from the lower edges of these sides are transversely curved jaws 60, adapted to be forced over the top of the barrel of the pistol, and having their free edges engaging the lower portion of the barrel. 90 Stops 61 may be formed upon the forward end of the jaws 60. As clearly shown in Fig. 4, the clip does not interfere with a 95 clear vision of the sight of the barrel.

The numeral 62 designates a finger or bracket secured to the casing 15, at its forward end, and this finger is adapted to engage within the forward end of the clip 57, while a bracket 62', having a vertical end 63, is adapted to engage with the rear end of the top of the clip. The bracket 62' is secured to the rear portion of the casing 15. It is obvious that the casing 15 may be securely held upon the clip 57, and may be 100 removed therefrom when desired.

I also provide means whereby the device may be carried in the sleeve of the user, and such means comprises a forward clip 64, provided at its forward end with a hook 65. 115 This hook engages in an opening or slot 66, in a plate 67, rigidly attached to the plate 31, (Fig. 5) and preferably formed integral therewith. The clip 64 has its rear portion slotted for connection with a longitudinally extensible elastic element 67', such as a section of elastic webbing. The elastic webbing 67' has its rear end secured in a slot 68, formed in a rear clip 69, having a bent end 70, adapted to engage over the edge of the sleeve opening, as shown in Fig. 9. Instead of employing the elastic webbing 67' it is obvious that I may employ a retractile coil spring or other elastic element.

When the device is applied to the barrel 130

6.4

of a pistol, gun or the like, it will serve to provide a light for shooting the fire arm in the dark. The button 41 may be moved rearwardly and contact 38 will engage the screw 35, and if the circuit is otherwise closed to the source of current, the bulb 45 will glow. In this closed circuit, current will flow from one pole of the source of current 56, through wire 54, plug 52, screw 32, plate 31, screw 48, the interior terminal 47 of the bulb 45, through the filament of the bulb, through the exterior terminal 46, socket 42, sleeve 26, cap 23, casing 15, contact 38, screw 35, plug 53, and through wire 55 back to the opposite pole of the source of current. Of course it is obvious that a second switch may be connected in either wire 54 or 55, as is desired.

In Fig. 9, the device is disconnected from the pistol or gun, and is shown carried within the sleeve 71 of the garment or coat. The hook 70 is engaged over the material 72 of the armhole. The elastic element 67 normally retains the casing 15 up in the sleeve, to permit of the user withdrawing the casing 15 from the sleeve, so that the same may be held in the hand of the user, and manipulated as an ordinary flash light.

It is to be understood that the forms of my invention herewith shown and described, are to be taken as preferred examples of the same, and that various changes in the shape, size, and arrangement of parts may be resorted to without departing from the spirit of my invention or the scope of the subjoined claims.

Having thus described my invention, I claim:

1. In an electric lamp of the character described, a casing, a lens held within the casing, a reflector held within the casing rearwardly of the lens, a cap for the rear end of the casing having electrical connection therewith, an insulating plate mounted upon the cap, a metallic plate mounted upon the rear side of the insulating plate, a sleeve arranged within the casing and having electrical connections with said cap, a socket mounted to slide longitudinally within the sleeve and having electrical connection therewith, a spring to move the socket rearwardly, a bulb held within the socket and having an interior terminal and an exterior terminal engaging the socket, an adjusting element having electrical connection with the metallic plate and engaging the interior terminal of the bulb to shift the bulb and its socket forwardly, an electrical connection engaging the metallic plate, a second electrical connection carried by the cap and insulated therefrom and from the metallic plate, and means for effecting an electrical connection between the second electrical connection and said metallic cap.

2. In an electric lamp of the character described, a casing, a lens held within the casing, a reflector held within the casing rearwardly of the lens, a cap connected with the rear end of the casing and having electrical connection therewith, an insulating plate mounted upon the cap, a metallic plate mounted upon the rear side of the insulating plate, a sleeve arranged within the casing and electrically connected with the cap, a socket slidable within the sleeve and electrically connected therewith, a bulb carried by the socket and having inner and outer terminals, one terminal engaging the socket, a spring to move the socket rearwardly, an adjusting screw having electrical engagement with the metallic plate and contacting with the other terminal of the bulb, an electrical connection contacting with the metallic plate and insulated from the cap, a second electrical connection carried by the cap and insulated therefrom and from the metallic plate, and a switch device having electrical connection with the casing and adapted to engage the second electrical connection.

3. In an electric lamp of the character described, a casing, a lens held within the casing, a reflector held within the casing rearwardly of the lens, a metallic cap carried by the casing, a metallic plate mounted upon the metallic cap and insulated therefrom, a sleeve arranged within the casing and electrically connected with said cap, a socket slidable within the sleeve and having electrical connection therewith, a spring to move the socket rearwardly, a bulb held within the socket and having an interior terminal and an exterior terminal engaging the socket, an adjusting element having electrical connection with the metallic plate and engaging the interior terminal of the bulb to shift the bulb and its socket forwardly, an electrical connection engaging the metallic plate, a second electrical connection carried by the cap and insulated therefrom and from the metallic plate, and means for effecting an electrical connection between the second electrical connection and said metallic cap.

4. In a readily portable electric lamp of the character described, a casing, a lens carried thereby, a bulb arranged within the casing rearwardly of the lens, adjustable means to support the bulb so that it may be shifted toward and away from the lens, said bulb having insulated terminals, a manually operated element engaging one terminal to supply current thereto and to shift the bulb in one direction, said manually operated element extending longitudinally of the casing and projecting outwardly beyond the rear end of said casing to be in convenient reach

of the fingers, means for connecting the manually operated element with one pole of a source of current, and means for connecting the other terminal of the bulb with the opposite pole of a source of current.

5. In an electric lamp of the character described, a casing, a lens carried thereby, a sleeve held within the casing and extending longitudinally thereof, a socket slidable within the sleeve, a bulb carried by the socket and having an exterior terminal engaging the socket and an interior terminal, an adjusting screw carried by the casing and engaging the interior terminal of the bulb and serving to shift the socket forwardly, means for connecting the screw with one pole of the source of current, and means for connecting the sleeve with the opposite pole of the source of current.

10. 6. In a device of the character described, a clip to be mounted upon the barrel of a fire arm, said clip including a hollow portion which is substantially V-shaped in cross section and having spaced sides and a top, said sides being provided with jaws to engage about the barrel of the fire arm, an electric lamp including a casing, a finger secured to one end of the casing and engaging beneath one end of said top, and a bracket secured to the casing and having a substantially vertical portion engaging the opposite end of such top.

15. 7. In a device of the character described, a clip to be mounted upon the barrel of a fire arm, said clip including a hollow body portion having spaced sides connected by a transverse portion, said sides being provided with jaws to engage about the barrel of the fire arm, an electric lamp including a casing, a finger secured to the casing and extending generally parallel therewith and engaging beneath one end of said transverse portion, and a coacting member secured to the casing and arranged generally at a right angle thereto and having a substantially straight

face to contact with the opposite end of said transverse portion.

8. In a device of the character described, a clip to be mounted upon the barrel of a fire arm, said clip including a hollow body portion having spaced sides connected by a transverse portion, means for securing said sides upon the barrel of the fire arm, an electric lamp including a casing, a finger secured to the casing and extending longitudinally thereof and engaging beneath one end of said transverse portion, and a coacting member secured to the casing and extending transversely thereof and adapted to contact with the opposite end of said transverse portion.

9. In a device of the character described, as a subcombination, a clip comprising a transverse portion having arms which converge away from said transverse portion, said arms being slightly spaced at their converged ends, spaced pins connecting said converged ends, the sight of the fire arm being adapted for insertion between the spaced converged ends and between said pins, and jaws carried by said arms adjacent to said pins and adapted to receive the barrel of the fire arm.

10. In an electric lamp of the character described, a casing, a lens carried thereby, a guide device held within the casing, a socket slidable within the guide device, a bulb carried by the socket and having an interior terminal and an exterior terminal engaging said socket, means for effecting the longitudinal movement of the socket within the guide device including a manually operated element engaging the interior terminal of the bulb, means for connecting the manually operated element with one pole of a source of current, and means for connecting the socket with the opposite pole of the source of current.

In testimony whereof I affix my signature:

RICHARD MAX EATON.
